UNITED STATES PATENT OFFICE

91,899

DESIGN FOR A BEVERAGE DISPENSING CABINET

Bertram T. Phillips, Chicago, Ill., assignor of one-fourth to Samuel E. Arnold, one-fourth to James P. Ryan, and one-fourth to Ernest E. Hinz, all of Chicago, Ill.

Application January 6, 1934, Serial No. 50,340

Term of patent 7 years

To all whom it may concern:

Be it known that I, BERTRAM T. PHILLIPS, a citizen of the United States, residing at Chicago, in the county of Cook and State of Illinois, have invented a new, original, and ornamental Design for Beverage Dispensing Cabinets, of which the following is a specification, reference being had to the accompanying drawing, forming part thereof.

The figure is a perspective view of a beverage dispensing cabinet, showing my new design.

I claim:

The ornamental design for a beverage dispensing cabinet as shown.

BERTRAM T. PHILLIPS.
